Primary Examiner — Terry A Wallace

(57) CLAIM

The ornamental design for an ice cream scoop, as shown and described.

DESCRIPTION

FIG. 1 is a front perspective view of an ice cream scoop showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the encircled portion in FIG. 1.

The broken lines in the drawings illustrate the portions of the ice cream scoop, which form no part of the claimed design. The dot-dash broken lines in FIG. 1 represent the boundary of the enlarged portion and form no part of the claimed design.

1 Claim, 9 Drawing Sheets
